R. J. Carlson

UNITED STATES PATENT OFFICE.

WILLIAM C. PARRISH, OF PORT ARTHUR, TEXAS.

DEEP-WELL PUMP.

Application filed April 16, 1924. Serial No. 706,796.

This invention relates to pumps and more particularly to pumps employed in deep wells such as oil wells and the like.

Broadly stated it is the object of the present invention to provide improved means for operating pumps of the character described capable of being employed at or near the bottom of relatively deep wells which are necessarily of small bore.

More particularly it is one object of the invention to provide pump operating mechanism of simple and compact construction which can be sunk to the bottom of a well and operated with a minimum of attention.

Another object relates to the provision of actuating means for such pumps which may be placed in the well, in combination with a source of energy for energizing the actuating means, the source of energy being positioned apart from the well.

Other objects will appear as the description of the invention progresses.

The accompanying figure of the drawing illustrates a diagrammatic elevation of the apparatus for operating the pump.

Referring to the drawing it will be seen that the pump shaft 24^a connected at its lower end to the pump (not shown) is arranged to be actuated by a plurality of electro-magnetic elements comprising armatures 61^a, 61^b, 61^c, 61^d, 61^e, 61^f, 61^g, and 61^h with cooperating solenoids 62^a, 62^b, 62^c, etc. The armatures are mounted loosely on the shaft 24^a and collars or shoulders 63 adapted to be engaged by the armatures are fixed to shaft 24^a. The several solenoid coils 62^a, 62^b, 62^c, etc. are connected in multiple with a suitable source of electrical energy. Thus the several coils are in multiple connection with lead wires 65 and 66, the latter of which is connected to one of the terminals of a battery or other source of electrical energy 64. The conductor 65 is connected by means of spring contacts 67 and 68 to a conductor 69 which is connected to the other terminal of the source of power 64. A circuit controller 70 is provided for actuating the spring contacts 67 and 68.

The several armatures 61^a, 61^b, 61^c, etc. are so arranged with respect to the several field coils 62^a, 62^b, 62^c, etc. that the maximum pull exerted by each armature will occur at a different time in the cycle of operation from that of the others. The maximum force exerted by an armature occurs just

previously to the time when it has reached the point of magnetic center with respect to its solenoid. Thus it will be observed that the armature 61^d is shown at the position 60 where it exerts its maximum pull and the several armatures beneath 61^d are in positions of progressively decreasing pulling power. The preferred arrangement is to so adjust the length of the stroke of the shaft 65 to the several armatures and their positions with respect to the solenoids that the maximum pull is first exerted by the armature at one end of the series, such as 61^a, and as the shaft moves the maximum pull is exerted 70 by the other armatures in succession. In the apparatus in the particular position illustrated armatures 61^a, 61^b, and 61^c are at points of magnetic center with respect to their solenoids. It will be observed, however, that since the armatures are loosely mounted on the shaft 24^a that they do not 75 impede the movement of the shaft when they are at points of magnetic center.

If desired, a plurality of sets of electro-magnetic elements may be provided. Thus for example, two sets may be used, the several elements of each set being so arranged that when the total pull exerted on the shaft by the elements of one set is at 85 a minimum the total pull exerted by the elements of the other set is at a maximum.

A modification of the invention is to provide in lieu of the slidably mounted armature 61^a, 61^b, etc. induction coils, using preferably two or three phase current.

Apparatus of preferred form and construction has been illustrated and described for the purpose of showing a way in which this invention may be practiced, but the inventive thought upon which this application is based is broader than this illustrative embodiment. It is therefore understood that the scope of the invention is not to be limited by the present disclosure, reference being had 95 to the appended claims for that purpose.

What I claim is:

1. An electric motor adapted to produce reciprocating motion of substantially uniform power over the entire range of an unidirectional stroke which comprises a movable shaft, a plurality of armatures mounted loosely upon said shaft, collars fixed on the shaft at equal intervals adapted to be engaged by the armatures, a plurality of solenoids connected in parallel and adapted to cooperate with said armatures,

said solenoids being equally spaced at intervals less than the intervals at which the collars on the shaft are spaced, a source of electrical power for the solenoids and contact means for energizing said solenoids during the working stroke of the shaft.

2. An electric motor adapted to produce reciprocating motion of substantially uniform power over the entire range of an 10 unidirectional stroke which comprises a movable shaft, a plurality of movable armatures loosely mounted upon said shaft, a plurality of solenoids connected in parallel and adapted to cooperate with said armatures,

collars fixed upon the shaft adapted to be 15 engaged by the armatures, said collars so positioning said armatures with respect to the corresponding solenoids that the maximum pull exerted upon the shaft by each individual armature takes place at a different time from that of the other armatures, a source of electrical power for the solenoids and contact means for energizing said solenoids during the working stroke of the shaft.

In witness whereof I have hereunto set 25 my hand this 7th day of March, 1924.

WILLIAM C. PARRISH.
